Inventor,

William L. Krumm

Maurice S. Gayne

Attorney

UNITED STATES PATENT OFFICE

WILLIAM L. KRUMM, OF CHICAGO, ILLINOIS

BOX

Application filed August 25, 1928. Serial No. 301,991.

The invention relates to a package or box, and particularly to a box for containing loose confections, such as hard candies, candied pop corn, and the like.

6 The main object of the invention is the production of a box, particularly adapted for loose confections, in which the box is of substantially triangular shape and formed from a single blank, and which may 10 be easily and cheaply made, compact, and neat and attractive in appearance.

Another object of the invention is the production of a box, particularly adapted for loose particles of food, such as candied 15 pop corn, nuts, raisins, a mixture of nuts and raisins, and the like, which is triangular in shape and formed from a single blank, and which is provided with a means for getting into the inside of the box at one 20 end thereof, and with a second means for reaching the inside of the box at one side thereof.

With the foregoing and other objects in view, which will appear as the description 25 proceeds, the invention consists in certain novel features of construction, arrangement, and combination of parts, hereinafter more fully described, illustrated in the accompanying drawings, and particularly pointed 30 out in the appended claims, it being understood that various changes in the form, proportion, size, and minor details of the construction may be made without departing from the spirit or sacrificing any of the advantages of the invention.

35 Stated generally, the invention comprises a single blank formed from any suitable material and from which a triangular box may be formed without the use of glue or any other fastening means. The improved box, 40 is intended for general use, but is especially adapted for holding loose particles of food. When in a fully assembled condition, the box has no free or loose edges, and is capable of 45 opening for reaching the contents thereof or for filling the same on two different sides.

For the purpose of facilitating an understanding of my invention, I have illustrated in the accompanying drawings a preferred embodiment thereof, from an inspec-

tion of which, when considered in connection with the following description, my invention, its mode of construction, assembly, and many of its advantages should be readily understood and appreciated.

55 Referring to the drawings, in which similar characters of reference are employed to indicate corresponding or similar parts throughout the several figures in the drawings:—

Fig. 1 is a plan view of the blank showing one form of the box;

Fig. 2, is a view in perspective showing the box formed by the folding of the blank 60 of Fig. 1, and

Fig. 3, is a sectional view taken on line 3—3 of Fig. 2.

Referring to the drawings more specifically, the numeral 10, designates a single blank from which the triangular box shown in 70 Fig. 2, is formed. This blank 10, may be formed from any suitable material such for example as relatively stiff paper stock, and comprises a triangular bottom member 11, two rectangular side members 12, and 13, a triangular top member 14, a rectangular end member 15, tucks 16, 17, and 18, provided on the ends of the rectangular side members 12, and 13, and tucks 19, and 20, provided 75 on the sides of said side member 13 and 15. The triangular members 11, and 14, are provided with overlapping flaps 21, and 22, respectively, said flaps being provided at the central portions thereof with suitable locking tongues 23, and 24, for a purpose 80 to be hereinafter described.

The end and side members 12, and 15, are formed on the sides of the bottom member 11, and the top or cover member 14, is 85 formed at the outer longitudinal edge of the end member 12. The end member 13, is formed at the base of the top member 14. The tucks 16, and 17, are formed with the ends of the side members 12, and 13, at 90 the side of the top member 14, and the tuck 18, is formed with the other end of the side member 13. The tuck 19, is formed at the outer longitudinal edge of the side member 13, and the tuck 20, is formed at the outer 95 longitudinal edge of the side member 15. 100

The flap 21, is provided at one side of the base member 11, and the flap 22, is provided at an opposite side of the top or cover member 14. Each of said flaps 21, and 22, is 5 provided with a locking tongue 23, and 24, respectively, said tongue being formed with the free longitudinal edges of said flaps. A lock slot 25, for the tongue 24, is formed between the bottom member 11, and the end member 15, and a second lock slot 26, for the tongue 23, is formed between the top member 14, and the end member 13.

The blank 10, is scored or cut creased to form folding lines A, between the bottom member 11, and the adjacent side members 12, and 15; folding lines B, between the end members 12, and 13, and the top member 14; folding lines C, between the flaps 21, and 22, and their adjacent members 11, and 14; folding lines D, between the end members 13, and 15, and their respective tucks 19, and 20; folding line E, between the side members 12, and 13, and their respective end tucks 16, 17 and 18; and folding lines F, between the flaps 21, and 22, and their respective tongues 23, and 24.

To form the box shown in the drawings, from the blank 10, the sides 12, and 15, are folded on the lines A. The tucks 20, and 30 16, are then folded on the lines D, and E, respectively. The top member 14, is next folded on the line B, and unto the tuck 20, into a position in which it is parallel with the bottom member 11. The tucks 17, 18, 35 and 19, are next folded on their respective folding lines D, and E, to a point where they will be substantially at right angles to the end member 13, which member is next folded along the line B, until stopped by the tuck 20, and its tucks 17, 18, and 19, are then inserted into the box between the top and bottom members 11, and 14. The flaps 21, and 22, are then folded along the 40 lines C, until they lie flat against their respective sides 13 and 15, and finally the tongues 23, and 24, are folded on the lines F, and their free end portions inserted through the slots 26, and 25 respectively.

The box is now in its fully folded and 50 assembled condition, as shown in Fig. 2, of the drawings, said assembly being accomplished without the use of glue or any other fastening means whatsoever. It will be noted that the said box when formed has no free edges, and that access to the inside of 55 said box may be obtained through either one of two sides thereof.

It is believed that my invention, its mode 60 of construction, and many of its advantages should be readily understood from the foregoing without further description; and should also be manifest that while a preferred embodiment of the invention has been shown and described for illustrative 65 purposes, the structural details are never-

theless capable of wide variation within the purview of my invention, as defined in the appended claims.

What I claim and desire to secure by Letters Patent of the United States is:—

1. A triangular box-forming blank having folding lines arranged to form a triangular base member, two rectangular side members one at each side of the base member, a triangular top member at the outer side of one of the side members, an end member at the outer side of said top member, tucks at certain of the ends of the side members, a flap formed with the free side of each of said top and bottom members, and tongues formed with each of said flaps at the free edges thereof and arranged to be inserted through slits in the end member and one of said side members, whereby when the blank is folded a triangular box is formed having the said flaps lying flat against the said end member and one of said side members, one of said tongues being inserted through the top of said box and the other of said tongues being inserted through the bottom of said box.

2. A foldable triangular box formed from a single blank closed at its top, bottom and sides, said blank being so shaped and scored as to provide when folded no free edges, 95 a flap formed with the free side of each of said top and bottom, a tongue formed with each of said flaps adapted for locking engagement with a portion of said box, whereby by said box is adapted for opening through 100 either of two sides thereof.

3. A foldable triangular box formed from a single blank closed at its top, bottom and sides, said blank being so shaped and scored as to provide when folded no free edges, 105 said box having a pair of overlapping flaps, and tongues on said flaps adapted for locking engagement with a portion of said box, said box being adapted for opening through either of two sides thereof.

4. A foldable triangular box formed from a single blank closed at its top, bottom and sides, two of said sides having superimposed flaps which are adapted to lie flat against said sides, and are provided with tongues for locking engagement with a portion of said box, said box being adapted for opening through either of two sides thereof.

5. A foldable box comprising superimposed rectangular side portions, triangular top and bottom portions, and a third rectangular side portion, said superimposed side portions having means for frictionally engaging with said top and bottom portions, whereby no free edges are provided on said 125 folded box, said box being adapted for opening through either of two sides thereof.

6. A foldable box comprising triangular top and bottom portions, two rectangular side portions, and a third rectangular side 130

portion, each of said triangular portions having an integral extension adapted to be superimposed on said first mentioned rectangular side portions, and means formed with said extensions adapted to frictionally hold said superimposed portions in assembled position when the box is folded, said box being adapted for opening through either of two sides thereof.

7. A foldable triangular box comprising top and bottom portions, and three side portions, two of said side portions having superimposed flaps, each of said flaps being provided with means for frictionally holding said flaps in superimposed relation, one of said means engaging the top of said box and the other of said means engaging the bottom of said box, said box being adapted for opening through either of two sides thereof.

20 In testimony whereof I affix my signature.
WILLIAM L. KRUMM.
